No. 744,652.

PATENTED NOV. 17, 1903

F. G. WALTER.

FLASH LAMP.

APPLICATION FILED NOV. 6, 1902.

NO MODEL.

UNITED STATES PATENT OFFICE.

FREDERICK G. WALTER, OF ALMOND, WISCONSIN.

FLASH-LAMP.

SPECIFICATION forming part of Letters Patent No. 744,652, dated November 17, 1903.

Application filed November 6, 1902. Serial No. 130,320. (No model.)

To all whom it may concern:

Be it known that I, FREDERICK G. WALTER, a citizen of the United States, and a resident of Almond, in the county of Portage and State 5 of Wisconsin, have invented certain new and useful Improvements in Flash-Lamps, of which the following is a specification.

This invention is an improvement in flash-lamps especially adapted for use in photography; and the objects of the invention are to provide means for quickly and effectively igniting the flash-powder, for spreading the flame, so as to give an intense flash-light for instantaneous photography or for other purposes, and also to provide means for preventing premature explosion or accidental ignition of the flash-powder.

Other objects and advantages of the invention will appear hereinafter, and what I claim 20 in the particular construction and combination of parts will be more specifically set forth in the appended claims.

In the accompanying drawings, which form a part of this specification, Figure 1 is a side elevation of a flash-lamp constructed in accordance with my invention. Fig. 2 is a plan view. Fig. 3 is a central longitudinal sectional view. Fig. 4 is a transverse sectional view on the line 4-4 of Fig. 2, the lamp being 30 removed.

Like letters of reference indicate like parts in the several views of the drawings.

Referring to said drawings, A designates a supporting frame or board, upon which are 35 mounted the pan for the flash-powder and the devices for igniting the latter, and centrally the said supporting frame or board is provided with means for attaching the same to a tripod for supporting it at the proper height. Said means of attachment consist of plates b 40 and b', secured to the upper and lower faces of the board, and a bolt b², the latter being adapted to pass loosely through the head of the tripod, lower plate, and board and engage a threaded opening in the upper plate, so as to clamp the parts together.

In the forward part of the supporting frame or board A is a vertical opening a, adapted to receive a removable oil-lamp C, which is 50 supported in the opening by lugs c c, projecting therefrom into an annular recess a'

in the side wall of the opening. Vertical recesses a², corresponding in number and location with the lugs c, extend downward from the annular recess, and when said lugs are 55 brought to register with said vertical recesses the oil-lamp may be removed from the lower part of the opening a, and to provide for turning the oil-lamp radial ribs c' are provided on the under side of the same. The 60 oil-lamp is of simple construction, comprising a bowl from the center of which projects a wick-tube, and to one side of the wick-tube is a filling-opening covered by a removable cap c². The shape of the lamp may be 65 changed, however, as well as the manner of attaching the same to the supporting frame or board A; but inasmuch as the flash-powder pan in the present instance overlaps the opening a it is necessary to insert the lamp 70 from the lower part of said opening, and therefore supporting means of some kind becomes necessary.

The pan for the flash-powder consists of a board D, secured to the forward end of the 75 supporting frame or board A transversely thereof, and upon this board is attached a metal plate d, upon which the flash-powder is placed. At the inner end of the wall D is a vertical wall d', and this wall is provided centrally immediately above the plate d with an opening d², through which the igniter passes 80 to the powder. Said opening is covered by a shutter or blade E, pivoted to the vertical plate d' and operated by a rod e, while the 85 throw of the shutter or blade is limited by stops e'. Upon the pan are mounted flame-spreaders F F, consisting of funnel-shaped boxes disposed on a line with their smaller ends adjoining each other, said adjoining ends 90 having openings f, while the side walls f' and f² are extended upward, as shown. These flame-spreaders or boxes are mounted on rods f², which extend through the supporting frame or board A and are threaded at their 95 lower ends to receive thumb-nuts, by which the flame-spreaders are clamped in an adjusted position.

G designates a horizontally-disposed tube or cylinder adapted to carry the igniter, and 100 this tube is mounted upon the upper end of a rod or standard H, passed vertically through

- the supporting frame or board A and adjustably secured thereto by set-nuts h and h' , which bear against the upper and lower sides of the supporting frame or board. In the 5 tube or cylinder G is mounted a piston i, carrying a rod i', which latter projects through the forward end of the tube and carries at its outer end a head j, of incandescing material, preferably copper, to provide the igniter. 10 Encircling the rod i', within the tube, is a helical spring s, forming a buffer, which causes the rebound of the rod after it is projected to its fullest extent. The tube and rod are so disposed with relation to the wick of the oil- 15 lamp that when the rod is retracted the head or igniter j will be over the wick of the lamp, so as to be heated by the flame. The piston and rod are operated by a bulb O and connecting-tube o, and in practice the said bulb 20 is also connected by T-coupling (see dotted lines, Fig. 3) to a tube leading to the camera-shutter, so that both the lamp and camera may be operated simultaneously. It will be understood also that where two lamps are to 25 be used they may be connected to the bulb by a T connection, as shown in Fig. 3. By providing a vertical adjustment for the horizontal tube or cylinder G the head or igniter may be caused to operate at any distance above 30 the surface of the pan.

The construction and operation of my improved flash-lamp will be readily understood from the foregoing description, in connection with the accompanying drawings, for, supposing a supply of flash-powder to be upon the pan, (in and between the flame-spreaders,) the hole d^2 to be open, and the head or igniter j to be heated to the required extent, pressure upon the bulb will force the piston 40 and rod forward, and the head or igniter j passing through the opening in the vertical wall d' into the flash-powder will explode the latter and produce an intense light, the intensity of the light being augmented by the 45 flame-spreaders, which produce a wider or flat flame.

The operation of the igniter is sure and effective, and the powder is exploded instantly upon contact of the igniter therewith. In 50 use the hole d^2 through the vertical wall d' of the pan is not opened until everything is ready for the photograph to be taken, and therefore said shutter will be very effectual in preventing a premature explosion or accidental ignition.

As heretofore stated, any style of lamp for heating the igniter may be provided, and in some cases it may be convenient to employ a gas-burner, and I do not, therefore, wish to 55 limit my protection to what is herein shown and described, as immaterial changes may be made in other parts of the device within the spirit and scope of my claims.

Having thus described my invention, what 60 I claim as new, and desire to secure by Letters Patent, is—

1. In a flash-lamp, the combination, of a pan

for the flash-powder having a vertical wall in rear of the same with an opening therethrough, a lamp, an igniter adapted to be heated by 70 said lamp, and means for moving the igniter through the opening in the vertical wall; together with a pivoted shutter adapted to cover said opening, and a rod for operating said shutter, substantially as shown and de- 75 scribed.

2. In a flash-lamp, the combination, of a pan for the flash-powder, a lamp, a tube mounted in the rear of the lamp, a piston in the tube carrying a rod having an igniter at its outer 80 end, and a bulb connected to the tube and by which the piston is operated.

3. In a flash-lamp, the combination, of a pan for the flash-powder, a lamp, a tube mounted in the rear of the lamp, a piston in 85 the tube carrying a rod projecting beyond the forward end of the tube and carrying an igniter at its outer end, a spring-buffer against which the piston abuts, and a bulb connected to the rear end of the tube for operating the 90 piston, substantially as shown and described.

4. In a flash-lamp, the combination, of a pan for the flash-powder having a vertical wall at its rear end with an opening through the same, a shutter pivoted to the vertical 95 wall and adapted to cover the opening, and a rod for operating said shutter; together with a lamp in the rear of said wall, a horizontal tube, a piston located in said tube and carrying a rod projecting beyond the forward end 100 of the same, an igniter on the forward end of the rod, and a bulb connected to the tube for operating the piston, substantially as shown and described.

5. In a flash-lamp, the combination, of a 105 pan for the flash-powder having a vertical wall at its rear end with an opening through the same, funnel-shaped flame-spreaders adjustably mounted on the pan in front of the vertical wall, a shutter pivoted to the vertical 110 wall and adapted to close the opening therein, a lamp, a tube, a piston in the tube carrying a rod projecting beyond the forward end of said tube and provided with an igniter, and a bulb connected to the tube and adapted to 115 operate the piston therein, substantially as shown and described.

6. In a flash-lamp, the combination, of a pan for the flash-powder, a lamp in the rear of the same, a vertically-adjustable rod or 120 standard supporting a horizontal cylinder, a piston in said cylinder, a rod carried by the piston and projecting beyond the forward end of the cylinder, an igniter on the outer end of said rod, and a bulb connected to the cylinder 125 for operating the piston.

7. In a flash-lamp, the combination, of the pan for the flash-powder, a lamp in the rear of the pan, a vertical standard passed through a support and adjustable thereon by set-screws bearing against the upper and lower sides of said support, a horizontally-disposed cylinder mounted on the upper end of said 130 rod or standard, a piston in the cylinder car-

rying a rod projecting beyond the former and having an igniter normally located over the flame of the lamp, a helical spring forming a buffer for the piston, and a bulb for operating said piston, substantially as shown and for the purpose set forth.

In testimony whereof I have signed this

specification in the presence of two subscribing witnesses.

FRED. G. WALTER.
